UNITED STATES PATENT OFFICE.

PIERRE JOSÉ BOUCHER, OF CHELSEA, LONDON, ENGLAND.

MACHINE FOR SEALING RECEPTACLES.

1,230,849.

Specification of Letters Patent. Patented June 26, 1917.

Application filed September 5, 1914. Serial No. 860,314.

To all whom it may concern:

Be it known that I, PIERRE JOSÉ BOUCHER, a subject of the King of Great Britain and Ireland, residing at 132 Lots' road, Chelsea, 5 London, England, have invented new and useful Machines for Sealing Receptacles, of which the following is a specification.

This invention relates to improvements in chucks for machines for hermetically sealing by an externally disposed cap or lid jars, bottles and the like used for preserves, jams, and the like, in which means are provided for automatically setting up a pressing and rolling action evenly all around the 15 outside of the metal band securing cap or lid, or metal cap as may be, so as to grip the underside of the collar or flange of the jar, bottle or the like and more particularly in cases where the top part of the jar or receptacle is not exactly circular; and consists in an improved construction whereby in addition to the above, effective sealing of the jar or receptacle is obtained when the plane of the face of the mouth of the said jar or 20 receptacle is not exactly at right angles to the axis of the body thereof, by the provision of a universally mounted holder the chuck being also provided with adjustable means to allow of sealing jars or receptacles with 25 flanges of different thicknesses.

In order that the invention may be the better understood I will now proceed to describe the same in relation to the accompanying drawing, reference being had to the letters and figures marked thereon. Like letters refer to like parts in the various figures, in which:

Figure 1 represents the side of the machine, part being in section and part in elevation.

Fig. 2 is a front elevation of the same.

Fig. 3 is a plan of the chuck disassociated from the machine showing the operating means for the sealing cones.

Fig. 4 shows a bottle neck associated with the sealing cones, the left hand cone being in the inoperative position during which the bottle neck is raised into position, and the right hand cone being shown in position for 45 effecting the pressing and rolling operation.

Fig. 5 shows a bottle neck associated with the sealing cones, and illustrates the manner in which said cones accommodate themselves to variations due to irregularities in 55 the shape of the receptacles being capped.

The working parts are mounted on a cast

iron frame or stand *a* with fast and loose pulleys *a'* and bevel gears *a''* the latter being keyed to their respective shafts *a³* and *a⁴*. The jar or receptacle to be sealed is placed 60 with metal band or cap in position on the lifting platform *b* adapted with means for raising or lowering to suit the height of jar or receptacle, such for example, as an adjustable collar *c* with set screws *c'* so that the jar or receptacle will pass under and clear the rotating parts prior to sealing. The jar or receptacle is then raised and held 65 in position by placing the foot on foot lever *d* and pressing it downward, said lever being elastically held by means of a spring *e*. As the action is taking place the cap enters the holder *f*, which is connected to the vertical shaft *a⁴*, by means of a screwed shank *f'* in order that the relative position 70 of the holder *f* to the sealing cones *o* may be modified to deal with flanges of different thicknesses. The bottom end of the screwed shank *f'* has a swiveling ball-joint *r* to allow the holder *f* to adapt itself to whatever angle the plane of the top of the said 75 jar may be to its axis.

Levers *g* are pivoted on the frame *a* and connected with them is the ring *h* which is held in the upward position by the spring *j*. 80 Links *k*, of which there are three shown in the drawing, are loosely pivoted at one end to the ring *h*, and at the other end to the knuckles *l*. The knuckles *l* are loosely pivoted in one end of the levers *n* which in turn 85 are pivoted on the chuck *m*, while the other end of the levers *n* carry the vertical stems *s* carrying the sealing cones *o* the said stems being disposed in slots *o'* in the chuck *m*. When the ring *h* is moved downward by the 90 lever *g* the cones *o* travel toward the center of the chuck *m* and vice versa. The cones *o* are preferably fitted with ball bearings on their stems *s* for easy turning, the ball bearings being slidingly arranged on the said 95 stem *s*; rubber buffers *o²* being provided to allow limited vertical movement of the cones *o* in order that compensation for the irregularities of the neck or flange of the jar may be provided for.

When the various parts are in position and at the correct height for the particular receptacle to be sealed the belt is first shifted from the loose to the fast pulley, thereby 100 rotating the vertical shaft *a⁴* and chuck *m* carrying the cones *o*, then by means of the lever *g*, the sealing cones *o* are brought in-

wardly into intimate contact with the edge of the metal cover surrounding the lip of jar or receptacle in such a way that lateral and vertical compression forces are impressed on 5 the metal so as to roll it inwardly under the lower edge of the lip of the jar or receptacle thus securing the metal band or cover in place.

The stems *s* carrying the sealing cones *o* 10 can alternatively be made with long bearings and have springs fitted below the cones *o* to permit the said cones *o* to accommodate themselves to variations due to the jars or receptacles being irregular in shape and out 15 of true as hereinbefore described.

Plates *q* are provided for keeping the jar or receptacle in position on the platform *b*.

I claim:

1. Apparatus for applying sealing bands 20 to capped receptacles and the like consisting of, in combination, a revolving chuck, a cap support universally mounted therein and adapted to remain stationary while the said chuck is revolving, a series of stems 25 depending from said chuck and adapted to have a movement to and from the axis of said chuck, means for operating said stems, a sealing cone freely mounted on each of said stems so as to both revolve and slide axially

thereon and an elastic device on each stem 30 adapted to press the said cone in a direction toward the portion of the band to be beaded over, substantially as described.

2. Apparatus for applying sealing bands to capped receptacles and the like consisting 35 of, in combination, a revolving chuck, a cap support universally mounted therein and adapted to remain stationary while the said chuck is revolving, means for adjusting the cap support relative to the chuck in an axial 40 direction, a series of stems depending from said chuck and adapted to have a movement to and from the axis of said chuck, means for operating said stems, a sealing cone freely mounted on each of said stems so 45 as to both revolve and slide axially thereon and an elastic device on each stem adapted to press the said cone in a direction toward the portion of the band to be beaded over, substantially as described. 50

In witness whereof I have signed my name to this specification in the presence of two subscribing witnesses.

PIERRE JOSÉ BOUCHER.
